UNITED STATES PATENT OFFICE.

EDWARD M. HENGELL, OF SAN FRANCISCO, CALIFORNIA.

ELECTRIC WATER-HEATER.

1,026,862.

Specification of Letters Patent.

Patented May 21, 1912.

Application filed December 19, 1910. Serial No. 598,109.

To all whom it may concern:

Be it known that I, EDWARD M. HENGELL, a citizen of the United States, and a resident of the city and county of San Francisco and State of California, have invented certain new and useful Improvements in Electric Water-Heaters, of which the following is a specification.

The invention relates to an electric water heater of that class or description which is adapted to be immersed in the water so that all of the heat generated by the passage of the electric current through the resistance element is imparted directly to the liquid.

15 The object of the invention is to provide a water heater in which the heating element is arranged close to the base, so that when placed in a vessel containing a small quantity of water, the heating element will be entirely covered.

Another object of the invention is to provide a heater having a neat and attractive appearance at a low cost of manufacture.

A still further object is to provide a 25 heater in which the heating element is arranged in a peculiar manner, so that a large amount of wire is contained in a small space, and so arranging the frame carrying the heating element that the water can 30 freely circulate through and around said heating element.

With these and other objects in view, as will more fully hereinafter appear, the invention consists of certain novel features of 35 construction and arrangement of parts hereinabove fully described, illustrated in the accompanying drawings, and particularly pointed out in the appended claims, it being understood that various changes in the 40 form, proportions, size and minor details of the structure may be made without departing from the spirit or sacrificing any of the advantages of the invention.

45 Referring to the drawings: Figure 1 is an elevation of the heater. Figs. 2 and 3 are plan views of the two frames which inclose the heating element, Fig. 2 being an inside view of one frame showing in dotted lines the position of the heating element. Fig. 4 is a cross section of the heater showing the means of holding the heating element in place.

The heater generally consists of the two frames 2-3 between which the resistance 50 element 4 is arranged, and by which it is held in place. The frames are composed of

some tough insulation material and are preferably formed of an outer circular ring 5 having arms or bars extending diagonally across. The bars 6 in the frame 2 are provided with concave recesses or grooves 7 on the under side to receive and hold the heating element. These grooves 7 are so spaced apart that when the heating element 4 is arranged therein, it lies generally in the form 65 of a spiral.

The bars 8 of the frame 3 are spaced apart in the same manner as those in the frame 2 with the result that when the frames are placed together in their proper positions, 70 the bars lie in line with each other, the bars 8 serving to press and hold the resistance element in the grooves 7. In this manner the resistance element is in contact with the frames only at those points where it contacts 75 with the bars.

To provide means for allowing the water to circulate around the heating element 4, I have provided short legs or off-sets 9 on the lower side of the rim of the upper frame 80 and on the upper side of the rim on the lower frame. These legs 9 are preferably arranged in line with the bars 6 and 8, so that the openings 12 formed when the frames are placed together, occur between 85 the bars. When the heater is in operation, the water passes in through the openings 12 and upward between the bars 6. In some instances, when it is desirable to provide for a greater circulation, I find it advisable to 90 arrange the short legs 14 on the under side of the lower frame so that the water can pass in below the frames and upward through them.

The heating element 4 consists of a helical 95 coil of wire of the required resistance, which is arranged in a spiral between the frames. By forming the heating element of helically wound wire, and then arranging such coil in a spiral, a greater length of wire can be arranged in a given space than if the wire were straight. The helix is so formed that when it is bent into a spiral, the successive turns of the helix will not contact with each other, and thereby short circuit such turns. The ends of the helix are connected to the binding posts, or terminals 15, on the bar 6. The insulated wires 16, to the end of which is attached a plug suitable for screwing into a socket on the supply mains, are attached 100 to the terminals on opposite sides of the bar 6, so that the heater will be balanced and lie 105 110

substantially horizontal when held by the wires 16.

The frames are held together by screws passing through the holes 17—18 in the bars 5 6—8, the holes on the underside of the bars 8 being countersunk to receive the head of the screw.

I claim:

1. An electric water heater comprising a 10 circular frame provided with diametrically disposed cross bars spaced apart vertically and a helically wound resistance element arranged spirally between said cross bars.

2. An electric water heater comprising 15 open circular frames, cross bars on said frames, the cross bars on one of said frames being recessed to receive the resistance element, a helically wound spirally arranged

resistance element and means for holding said frames together to confine the resistance element.

3. An electric water heater, comprising circular frames, cross bars on said frames, legs spaced apart circumferentially of the frames adapted to hold the frames apart 25 and to provide openings between the frames, a helically wound resistance element arranged spirally between said frames, the cross-bars of one of said frames being recessed to receive the resistance element, and 30 terminals on one of said cross bars.

EDWARD M. HENGELL.
